UNITED STATES PATENT OFFICE.

WILLARD C. WILLIAMS, OF INDIANAPOLIS, INDIANA.

FEEDER FOR EXPLOSION ENGINES.

Application filed June 15, 1921. Serial No. 477,750.

To all whom it may concern:

Be it known that I, WILLARD C. WILLIAMS, a citizen of the United States of America, residing at Indianapolis, in the county of Marion and State of Indiana, have invented new and useful Improvements in Feeders for Explosion Engines, of which the following is a specification.

The object of the invention is to provide means for supplying heated moisture carrying air to the explosive mixture as an ingredient thereof for the purpose of effecting a complete combustion of the charge at each explosion of the engine and of conveying said combustion supporting agency to the intake manifold of the engine under such conditions as to insure the perfect mixture and uniform commingling of the fuel and combustion supporting agent and a complete vaporization of the fuel prior to its admission to the cylinder; and with these objects in view the invention consists in a construction and combination of parts of which a preferred embodiment is shown in the accompanying drawings, wherein:

Figure 1 is a view of an engine of the Ford type having arranged in operative relation therewith a fuel feeding apparatus constructed in accordance with the invention.

Figure 2 is a vertical sectional view of the retort.

Figure 3 is a vertical sectional view of the radiator cap.

Figure 4 is a detail view of the operating rods.

Fig. 5 is a sectional elevation taken on the line 5—5 of Fig. 2.

Fig. 6 is a cross-sectional view of the lower portion of the retort.

The invention contemplates conducting a supply of moisture laden air from the radiator 10 as the most convenient and accessible source thereof through the zone exposed to the heat of the exhaust manifold 11 of the engine of which a typical form is shown at 12, and introducing the same into a mixing and atomizing retort 13 with which communicates the carbureter 14, under such conditions as to insure an effective commingling of the moisture laden air with the carburetted air received from the carbureter in proportions which can be controlled and which are regulable automatically or other-

wise to suit the conditions under which the engine is operating.

In carrying out this object there is employed an air feed tube 15 which has its inlet end in a radiator cap extension 16 removably fitted as by being threaded upon the radiator cap tube 17, said extension being provided with suitable thumb holds 18 to facilitate application and removal when the radiator is to be filled in the ordinary way. Also communicating with the radiator cap extension is an air intake tube 19 to supply air which is removed through the feed tube 15.

This feed tube extends longitudinally of the exhaust manifold in close proximity to or through the same as indicated, respectively in full and dotted lines in Figure 1 within the heat zone thereof so that the moist air received by the tube from the radiator, and due to the evaporation of the water in the radiator is raised to a relatively high temperature in its passage to the retort 13.

The discharge of the heated moist air from the feed tube 15 into the retort 13 is in an upward direction at the bottom of the latter by means of a spray or distributing nozzle 20 acting as a blower by reason of the suction to which the contents of the retort are exposed on the intake or induction strokes of the cylinder pistons, by reason of the connection of the retort through its outlet 21 with the intake manifold 22, said nozzle having a cylindrical wall 23 fitted with a distributing cap plate 24 which is provided with a beveled peripheral edge spaced slightly from the beveled upper edge of the wall 23 to cause an upwardly expanding column of air from the nozzle as it enters the vaporizer as shown by the arrows in Figure 2. The inlet through the nozzle is also controlled to a certain extent by a gravity actuated or yieldingly seated valve 25 which is mounted to unseat inwardly or when exposed to the reduction of pressure in the retort.

The carbureter inlet 26 to the retort is disposed at one side of the latter substantially in the horizontal plane of the outlet of the nozzle 20 so that as the carburetted air is inducted from the carbureter into the retort it is exposed to the upwardly directing flaring column of heated moisture laden

air by the same influence through the nozzle and the columns of carburetted air and moisture laden air thereby intersect and are brought into a more or less intimate relation 5 tending to induce thorough commingling thereof.

Disposed in the path of upward movement of the vapor represented by the mixture of carburetted air and moisture laden 10 air due to the reduction of pressure at the top of the retort on the suction strokes of the engine pistons is arranged a baffle plate 27 serving to impede the upward progress 15 of the column of vapor and distribute it for passage through a gauze wire screen of annular form as shown at 28 surrounding the baffle plate and serving as the only means 20 of communication between the lower or inlet chamber B of the retort and the upper or discharge chamber A thereof.

Furthermore and also arranged transversely in the retort above the plane of the baffle plate 27 there is arranged a second baffle plate 29 fitted with a multiplicity of 25 minute tubes 29^a arranged in inclined relation to the plane of the plate 29 and also in inclined relation to the axis of the retort or the normal path of progress of the vapor from the lower to the upper end of the retort, said tubes being inclined in a common 30 or spiral direction so that the mixture of vapors in passing therethrough as the only means of communication between the spaces below and above the said plate receive a circulatory or gyratory or swirling movement 35 in which condition they approach the outlet 21 which in turn is controlled by a throttle valve 30 of which the stem 31 is provided with an operating lever 32 under the control 40 of the operator of the car through a suitable operating rod 33.

The carbureter needle valve 34 is also under the control as in the ordinary practice 45 of the operator through an operating rod 35 extending as indicated to the dash board 36 and in practice a connection is established between the throttle valve operating rod 33 and the needle valve operating rod 35 as shown in detail in Figure 4 to the 50 end that when the gas controlling lever is operated by the driver to unseat the needle valve of the carbureter the throttle valve is also opened proportionately but the carbureter valve is opened slightly in advance 55 of the throttle or feeder valve and is also closed more quickly or in advance of the feeder throttle valve. To this end means of adjustment are provided between the rods 33 and 35, as shown in Figure 4 wherein said 60 rods are provided respectively with turn buckles 33^a and 35^a and an adjustable connecting plate 37 is employed to connect the said rods, the same being terminally attached to the rod 35 and adjustably connected with the rod 33.

It will be obvious that in the operation of the apparatus the suction of the engine on the intake strokes of the cylinder pistons causes an induction of hot moist air from the feed tube 15 into the retort where it immediately comes into intimate contact with 70 the carburetted air from the carbureter, in a finely divided or expanded condition due to the construction of the discharge nozzle 75 20 and the relative positions of said nozzle and gas inlet, the valve 25 being unseated by the suction to permit of the inflow of said hot moist air. This valve being located at the entrance to the retort automatically 80 controls the amount of air introduced when the engine is idling or running without a load, and when the engine is being speeded the practically continuous pressure thereon due to the rapid intake strokes of the engine 85 serves to hold the valve in a raised position so as to admit the full capacity of the air tube. Upon passing the control valve 25 the air in the sprayed condition above indicated passes up into the lower chamber of the retort where it practically envelopes the 90 spray of vapor introduced from the carbureter, whether of gasoline or kerosene and completes the operation of vaporizing the fuel by reason of the temperature of the column of air. The mixture of hot moist 95 air and vaporized fuel then comes into contact with the baffle plate or spreading disk 27 and is distributed to pass through the screen which may as illustrated be formed in a frame consisting of the plate 27 which 100 is threaded at its periphery into the vaporizer. From the screen the mixture of vapors passes through the circulating or swirl plate consisting of the baffle 29 and the angularly directing tubes 29^a thereof where 105 they receive a gyratory movement and in this condition approach the valve control outlet 21 for passage to the cylinders.

The result of the indicated preparation of the fuel in the operation of the engine is 110 that the formation of carbon is minimized and the motor is as a consequence adapted to run more quietly, smoothly and efficiently, with the minimizing of the consumption of fuel in proportion to the energy produced. 115

It is further claimed in this connection as an advantage of the interposing of the feeder between the carbureter and the intake manifold that not only is there no ill effect 120 incident for example to a tendency to objectionably retard the feed of the fuel to the cylinders but that on the other hand the feeder tends to eliminate the induction into the cylinders of a useless amount of gas which ordinarily reaches the same when a 125 direct connection is made between the intake manifold and the carbureter. With this attachment the needle valve can be adjusted much more closely or with a smaller opening 130 or passage for the gas, and when operating 135

on long runs as in touring it is possible to reduce the needle valve opening materially and hence proportionately reduce the consumption of the gas without detracting from the efficiency of the motor.

It should further be understood in this connection that while as a matter of convenience the feeding apparatus has been shown in connection with a particular type 10 of motor, its utility is not limited to any one type but with slight variations in the connections may be applied generally to the motors of any of the commercial or other types of automobiles, tractors, stationary 15 engines or the like and whether the fuel employed is gasoline or kerosene.

Having described the invention, what is claimed as new and useful is:—

1. A feeder for interposition between a 20 carbureter and an intake manifold and having a retort interiorly subjected to suction due to the induction strokes of the motor pistons and means for supplying the retort with moisture laden heated air, the retort 25 having a carbureter inlet arranged between the air inlet and the point of communication with the intake manifold.

2. A feeder for interposition between a carbureter and an intake manifold and having 30 a retort interiorly subjected to suction due to the induction strokes of the motor pistons, and an air feed tube extending from the radiator through the heated zone of the exhaust manifold to the retort at a point 35 remote from the communication of the latter with the intake manifold, the retort having a carbureter inlet disposed between the air inlet and the outlet to the manifold.

3. A feeder for interposition between a 40 carbureter and an intake manifold and having a retort interiorly subjected to suction due to the induction strokes of the motor pistons, a distributing nozzle arranged in the retort at the opposite end from the communication 45 thereof with the intake manifold and means for supplying said nozzle with moisture laden heated air, said nozzle having means for discharging an upwardly flaring column of air intersecting the column of vapor inducted from the carbureter.

4. A feeder for interposition between a carbureter and an intake manifold and having 50 a retort interiorly subjected to suction due to the induction strokes of the motor pistons, a distributing nozzle arranged in the retort at the opposite end from the communication thereof with the intake manifold and means for supplying said nozzle with moisture laden heated air, said nozzle having means for discharging an upwardly flaring column of air intersecting the column of vapor inducted from the carbureter and provided with a normally seated inwardly opening pressure actuable controlling valve.

5. A feeder for interposition between a

carbureter and an intake manifold and having a retort interiorly subjected to suction due to the induction strokes of the motor pistons, a distributing nozzle arranged in the retort at the opposite end from the communication thereof with the intake manifold and means for supplying said nozzle with moisture laden heated air, said nozzle having means for discharging an upwardly flaring column of air intersecting the column of vapor inducted from the carbureter and provided with a normally seated inwardly opening controlling valve unseatable by reduction of internal pressure.

6. A feeder for interposition between a carbureter and an intake manifold and having 80 a retort interiorly subjected to suction due to the induction strokes of the motor pistons, a distributing nozzle arranged in the retort at the opposite end from the communication thereof with the intake manifold and means for supplying said nozzle with moisture laden heated air, a baffle being interposed between the nozzle and the exhaust into the intake manifold and provided 85 with spirally disposed passages therethrough for imparting a gyratory movement to the vapors.

7. A feeder for interposition between a carbureter and an intake manifold and having 90 a retort interiorly subjected to suction due to the induction strokes of the motor pistons, a distributing nozzle arranged in the retort at the opposite end from the communication thereof with the intake manifold and means for supplying said nozzle with moisture laden heated air, a swirl plate being interposed between the nozzle and the outlet to the intake manifold and consisting 95 of a plate having tubular vapor directing 100 passages arranged at an inclination to the path of movement of the vapors.

8. A feeder for interposition between a carbureter and an intake manifold and having 105 a retort interiorly subjected to suction due to the induction strokes of the motor pistons, a distributing nozzle arranged in the retort at the opposite end from the communication thereof with the intake manifold and means for supplying said nozzle with 110 moisture-laden heated air, an inlet from the carbureter being provided in the retort between the plane of the nozzle and the outlet to the intake manifold, and a baffle interposed between the nozzle and the outlet into 115 the intake manifold and also between the carbureter inlet and said intake manifold and surrounded by an atomizing screen.

9. A feeder for interposition between a carbureter and an intake manifold and having 120 a retort interiorly subjected to suction due to the induction strokes of the motor pistons, a distributing nozzle arranged in the retort at the opposite end from the communication thereof with the intake mani- 125

130

fold and means for supplying said nozzle with moisture-laden heated air, an inlet from the carbureter being provided in the retort between the plane of the nozzle and the outlet to the intake manifold and directed to discharge in a path transverse to and intersecting the path of discharge from said nozzle, and a baffle interposed between

the nozzle and the outlet into the intake manifold and also between the carbureter inlet and said intake manifold and surrounded by an atomizing screen.

In testimony whereof he affixes his signature.

WILLARD C. WILLIAMS.
